UNITED STATES PATENT OFFICE.

CARL F. KRAUSE AND RUDOLF C. KRAUSE, OF WESTFIELD, WISCONSIN.

MARINE BICYCLE.

956,533.

Specification of Letters Patent.

Patented May 3, 1910.

Application filed July 1, 1909. Serial No. 505,476.

To all whom it may concern:

Be it known that we, CARL F. KRAUSE and RUDOLF C. KRAUSE, citizens of the United States, residing at Westfield, in the county 5 of Marquette, State of Wisconsin, have invented certain new and useful Improvements in Marine Bicycles; and we do hereby declare the following to be a full, clear, and exact description of the invention, such as 10 will enable others skilled in the art to which it appertains to make and use the same.

This invention relates to marine bicycles, and has for one of its objects to improve the construction and increase the efficiency and 15 utility of devices of this character.

With this and other objects in view, the invention consists in certain novel features of construction as hereafter shown and described and then specifically pointed out in 20 the claims, and in the drawings illustrative of the preferred embodiment of the invention, Figure 1 is a side elevation of the improved device. Fig. 2 is a transverse section on the line 2—2 of Fig. 1. Fig. 3 is a plan 25 view of the improved device. Fig. 4 is a longitudinal section on the line 4—4 of Fig. 3. Fig. 5 is an end elevation viewed from the bow.

The improved device comprises two boats 30 10—11 spaced apart, the boat 10 being provided with a longitudinal elevated member 12, and the boat 11 provided with a similar longitudinal member 13. Extending across the members 12—13 near their ends are tie 35 members 14—15, said tie members being recessed into the members 12—13. The members 12—13 and 14—15 form a frame whereby the boats are firmly united, and maintained in their spaced relations, with their keel- 40 lines in parallel relations. Bearing upon the members 14—15 is a supporting platform or deck formed in two sections 16—17, the confronting edges of the platform members being spaced apart midway between 45 the two boats.

Bearing upon the deck portions 16—17 is a longitudinal housing, preferably formed of relatively heavy sheet metal or plate metal and comprising the body portion 18 50 and lateral flanges 19—20, the flanges being arranged to bear respectively upon the deck portions 16—17 and rigidly connected thereto by bolts, screws, or other suitable fastening devices 21—22.

Connected beneath the transverse members 14—15 is a longitudinal supporting

member 23, the latter extending at the bow and stern portion of the deck members 16—17, as shown. The member 23 is provided at the forward or bow end with a longitudinal slot 24 in which a chain wheel 25 is mounted for rotation upon a shaft 26, while a similar slot 27 is formed in the stern portion of the member 23 and in which a chain wheel 28 is mounted for rotation upon a 60 shaft 29. An endless chain 30 is mounted upon the chain wheels 25—28, the lower side of the chain being thus arranged to move close to the water line. Connected to the chain 30 at suitable intervals are paddles 31, 65 as many of the paddles as required being employed. The paddles are arranged to move in the water when the chain is operated, as will be understood. The chain wheels 25 and 28, the chain 30, and its paddles 31 are so arranged that the upper side of the chain and its paddles pass through the housing 18, as shown.

Mounted for rotation in the member 23 rearwardly of the chain wheel 28 is a rudder post 32 having a rudder 33, and with a cable sheave 34 at the upper end of the rudder post.

Mounted upon the deck members 16—17 is a supporting frame, preferably constructed 85 from tubing similar to ordinary bicycle frames, and comprising a "back-bone" member 35, forwardly arranged oblique brace members 36—37 and rearwardly arranged oblique brace members 38—39. The 90 brace members 36—37 are coupled to the "back-bone" 35 by a coupling element 40, while the brace members 38—39 are coupled to the back-bone member by a coupling element 41. The lower terminals of the various 95 brace members are seated in socket plates attached by bolts, screws or other fastening means to the deck members, and as these socket plates are precisely alike they are designated by the single character 42. 100 By this means a rigid supporting frame is provided to which the operating mechanism is connected, the parts being constructed and united, as before stated, in the same manner as an ordinary bicycle frame. 105

Formed in the back bone member 35 near the forward end is a bearing 43 through which a vertical post member 44 is mounted for rotation, the post member stepped at its lower end at 45 upon the housing 18 and 110 provided at its upper end with a turning wheel 46. Connected to the post 44 is a

cable sheave 47. Mounted for rotation upon the deck member 16 are spaced guide sheaves 48—49, and similarly mounted for rotation upon the deck member 17 are similar guide sheaves 50—51. A cable 52 leads from the sheave 34 of the rudder post to the sheave 47, and passing around the guide sheaves 48—49, while a similar cable 53 is connected to the sheaves 34 and 47 and passes around the guide sheaves 50—51. By this means it will be obvious that oscillatory motion imparted to the post 44 by the steering wheel 46 will control the movement of the rudder 33. Idler guide sheaves 54—55 may be arranged to control the movement of the cables 52—53, and cause them to run truly over the various sheaves, as will be obvious.

Formed in the back-bone member 35 near its rear end is a socket 56, and supported in this socket is a post member 57, the latter being preferably arranged at a forwardly extending angle. The post 57 is suitably supported from the brace members 38—39 by diagonal braces 58—59. The upper end of the post 57 is utilized to support a seat 60 of the usual form employed upon bicycles, and mounted for rotation in the lower end of the post 57 is a crank axle 61 having treadles 63—62 at its ends, the crank axle and the treadles being of the usual form employed upon bicycles. A chain wheel 67 is connected to the crank axle 61, and a smaller chain wheel 64 is connected to the shaft 29 alongside the chain wheel. A driving chain 65 is arranged to lead over the chain wheel 63—64. By this means a person occupying the seat 60 and operating the treadles, will thus impart motion through the chain 65 to the shaft 29 and then to the chain 30 and its paddles 31. The steering wheel 46 will be located in the same position relative to the seat as in an ordinary bicycle. The housing 18 is cut away as represented at 66 to permit the chain 65 to operate, as represented in Fig. 1.

The improved device is simple in construction, can be inexpensively manufac-

tured, is compact, strong and durable, and thus able to withstand the severe strains to 50 which it will be subjected when in use, or when operating upon rough water

What is claimed is:—

1. In an apparatus of the class described, two boats spaced apart, an upwardly directed base member extending longitudinally of each boat, each base member being provided with spaced recesses, transverse members engaging in said recesses and secured to said base members, deck members 60 connected to said transverse member with their inner edges spaced apart, an upwardly arching housing connected to said deck members and extending over the space between the same, a supporting member 65 connected beneath said transverse members and extending at the ends forwardly and rearwardly of the deck members, chain wheels mounted for rotation upon said supporting members, an endless chain carrying a plurality of paddles spaced apart and operating over said chain wheels, and chain operating means supported upon said deck members.

2. In an apparatus of the class described, 75 two boats spaced apart, deck members carried by said boats with their inner edges spaced apart, an upwardly arching housing connected to said deck members and extending over the space between the same, a supporting member connected beneath said deck members and extending at the ends forwardly and rearwardly of the deck members, chain wheels mounted for rotation upon said supporting member, an endless chain 80 carrying a plurality of paddles spaced apart and operating over said chain wheels, and chain operating means supported upon said deck members.

In testimony whereof, we affix our signatures, in presence of two witnesses.
